US00D762366S

(12) **United States Design Patent**
Granger et al.

(10) **Patent No.:** **US D762,366 S**
(45) **Date of Patent:** **** Aug. 2, 2016**

(54) **SHOE INSOLE**

(71) Applicant: **Spenco Medical Corporation**, Waco, TX (US)

(72) Inventors: **David B. Granger**, Lorena, TX (US); **Jacob Martinez**, Temple, TX (US)

(73) Assignee: **Spenco Medical Corporation**, Waco, TX (US)

(**) Term: **15 Years**

(21) Appl. No.: **29/531,338**

(22) Filed: **Jun. 25, 2015**

(51) **LOC (10) Cl.** 02-04

(52) **U.S. Cl.**

USPC **D2/961**

(58) **Field of Classification Search**

(57) **CLAIM**

The ornamental design for a shoe insole, as shown and described.

DESCRIPTION

FIG. 1 is a perspective view of a shoe insole showing our new design;

FIG. 2 is a bottom view of a shoe insole shown in FIG. 1;

FIG. 3 is a top view of a shoe insole shown in FIG. 1;

FIG. 4 is a medial side view of a shoe insole shown in FIG. 1;

FIG. 5 is a lateral side view of a shoe insole shown in FIG. 1;

FIG. 6 is a front side view of a shoe insole shown in FIG. 1; and,

FIG. 7 is a back side view of a shoe insole shown in FIG. 1.

1 Claim, 5 Drawing Sheets
